UNITED STATES PATENT OFFICE

WILLIAM E. McCULLOUGH, OF KENOSHA, WISCONSIN, ASSIGNOR TO SIMMONS COMPANY, OF KENOSHA, WISCONSIN, A CORPORATION OF DELAWARE

HYDRAULIC PRESS

Application filed April 1, 1929. Serial No. 351,590.

The present invention concerns a novel form of hydraulic press of the type used in plastic molding, die hobbing, and similar operations.

5 One of the objects of the invention is to provide a variable total pressure or lift press having a multiple plunger, that is to say, having a plunger that is divided into a number of pressure-receiving portions, upon one 10 or all of which portions pressure may be applied at will.

Another object of the invention is so to construct the hydraulic press that the same 15 may be closed comparatively rapidly by applying pressure to the main cylinder area of the plunger and thereupon additional power may be secured by applying additional pressure to a further portion of the said plunger, whereby the total surface area subjected to 20 the hydraulic pressure of the high pressure water supply may be increased.

Another object of the invention is to so construct the hydraulic press that the reverse movement or the downward movement 25 of the cylinder may be accelerated by applying hydraulic pressure to the same instead of depending upon its weight as is usually the case, and to accomplish this without employing separate push-back cylinders.

30 A further object of the invention is so to construct a hydraulic press of the type hereinafter described as to allow ready access to the packing rings of the same, and also to enable repairs to be made thereto without the 35 necessity of dismantling the press.

A still further object of the invention is so to construct a hydraulic press that different total pressures upon the platen of the same may be obtained by using any or all 40 of the pressure chambers, one of said pressure chambers being in annular form.

Other objects of the invention will appear 45 in connection with the drawings and specification which form a part of the present application, and in which drawings:

Figure 1 is a vertical drawing, partly in section, showing the constructional details of the press insofar as necessary to explain the present invention; and

50 Fig. 2 is a top view of the press; and

Fig. 3 is a sectional view, along the line 3—3 of Fig. 1, looking downwardly in the direction of the arrows;

Fig. 4 shows, in diagrammatic view, the top of a platen having a plurality of plungers attached thereto, this being a modification of my device considered to be a mechanical equivalent thereof.

As will be seen from Fig. 1, my improved hydraulic press consists of a foundation frame 10 which is, preferably, because of convenience of operation, placed in a wall 11 below the floor line 12 so that the platen 17 of the press will be at proper operating height to allow of convenient attendance by the operator. Upon this frame 10 there are erected steel uprights 13 which are attached to the foundation supports 10 by large nuts 14. At the upper end of the supports 13 there is attached the head 15 which may be of the ordinary conventional design such as is commonly used with hydraulic presses. This head 15 rests upon an off-set 16 located near the upper end of the upright supports 13 and is held fast thereto by means of the nuts 14a.

In slidable engagement with the uprights 13 is the platen 17, which, in turn, has mounted upon it either rigidly attached or simply laid thereon a number of pressure bars 18 55 surmounted by a steel plate 19. Similar bars 18a and 19a are attached to the head 15 of the press. This part of the press equipment may be of the regular standardized construction and is therefore shown on the drawings in conventionally diagrammatic form. The

hydraulic portions of the press consist of an outer water tight lower casing 20, in which a plunger or pressure head 21 is movable upwardly and downwardly, a water tight seal between the walls of the casing 20 being provided and consisting of rubber or leather gaskets 22. These gaskets are annular in shape and lie within a suitable groove within the plunger head 21. The said gasket 22 is held in place by an annular ring 23 which is bolted into the plunger head 21 by means of the bolts 24 and the nuts 25.

Attached to the plunger head 21 there is a cylindrical vertically disposed ram 26, the latter being fastened to the plunger head by

60

- means of the cap screws 27'. As an upper closure for the lower casing 20 there is provided an annular transverse horizontally disposed partition 27 which is bolted to an enlargement at the upper end of the casing 20 by means of the bolts 28, a suitable, preferably lead, gasket 29 serving to form a water tight and pressure tight seal between the casing 20 and the head 27.
- 10 The ram 26 aforesaid passes through the central opening in the annular partition 27, a water tight seal between the partition 27 and the ram 26 being assured by a leather or rubber gasket 30 which is held in place by an annular ring 31 fastened to the partition 27 by means of the bolt 32 and the nut 33. As will be seen from Fig. 1 this provides an annular external chamber 34 which is bounded on the outer periphery by the casing 20 and on the inner periphery by the ram 26. The casing 20 is completed on its lower surface by a dome-shaped end piece 35 which is, preferably, cast as a single piece with the casing 20 as it must withstand high hydraulic pressure. An inlet pipe 36 serves to supply water into the space 49 between the plunger head 21 and the dome-shaped end piece 35.
- 15 The ram 26 is elaborated just beyond the transverse closure piece 27 into an internally hollow enlarged ram 26a which, in turn, has the platen 17 of the press bolted to it by the bolts 37 and 38. This upper portion 26a of the ram operates within a cylindrical casing 39 which is also bolted at its lower end to the partition 27, a water tight seal between said partition and casing 39 being assured by a, preferably lead, gasket 40. A similar water tight seal between the ram 26a and the casing 39 is secured by means of the gaskets 25 41 which are held in place by the annular ring 42 which is held to the casing 39 by means of the bolt 43 and the nut 44.
- 20 A water inlet 45 is provided in the wall of the casing 20 so that water may be admitted to the annular space between the casing 20 and the ram 26. A similar water inlet 46 is provided in the wall of the casing 39 so that water may be admitted to the annular space 47 which exists between the enlarged portion 26a of the ram and the upper cylindrical casing 39 and the partition 27.
- 25 The platen 17 of the press is provided with laterally extending lugs 17a. The transverse horizontally located partition 27 is also provided with similar laterally extending lugs 27a, these lugs having bolt holes 17b and 27b, respectively, so that a connecting yoke 48 may be inserted between the lugs 17a and 27a, suitable bolts being inserted into the holes 17b and 27b. In the ordinary operation of the press, these yokes 48 are not in place and their use will be described hereinbelow in discussing the mode of operation of my improved selective pressure hydraulic press.

The press is secured to the foundation frame 10 and to the floor of the pit 11 by means of large lag bolts 10a. It is also to be understood that there are suitable valves controlling the water to be admitted through the three water inlet pipes 36, 45 and 46, respectively, although these valves are not shown as the press is operated by remote control through a complicated system of pipes, valves, plungers and cams which form the subject matter of copending application Serial No. 357,736, filed April 24, 1929. It is also to be understood that the steel plate 19 surmounting the platen 17 serves to receive the dies or molds which serve to fashion the article that is to be molded on the press. These parts are not shown, as they are not essential to the present invention. It will be noticed that when the press is in an entirely open position, as illustrated in Fig. 1, that there is still an appreciable space 49 between the dome-shaped end piece 35 and the plunger head 21.

The operation of my press is easily understood. There is supplied to the press, by means of suitable piping, two kinds of pressure water, the first being designated as low-pressure water, being supplied at a pressure of about 80 lbs. to the square inch, such as is usually available from city or private water supplies. The second supply of water is water coming through suitably heavy piping from an hydraulic pump and accumulator, this water being at, say, 1,000 lbs. pressure per square inch. It is to be understood that both high-pressure water as well as the low-pressure water may be applied through the inlets 36 and 46, although it is contemplated that only low-pressure water be admitted to the press through the inlet 45. Without limiting myself in any way to the dimensions given, let it be assumed for the purpose of illustration that the total area of the plunger head 21 exposed to the hydraulic pressure of the water admitted through the inlet 36 would be 254 square inches, which would correspond to an internal diameter of the casing 20 of 18 inches. Then if the water pressure applied through the inlet 36 were at 1,000 lbs. per square inch, this would correspond to a total pressure of 254,000 lbs. which would be communicated through the rams 26 and 26a to the platen 17 of the press. In other words, in using only the lower water-inlet 36 and the water-space 49, the effective total lift of the press will be 254,000 lbs. or 127 tons.

All of the presses known to me in the past merely have a single water space and a single cylindrical ram so that the pressure upon the press, that is to say, the total lift, can only be changed by changing the pressure of the high-pressure water. In accordance with my construction, however, I am able to gain selective pressures without necessitating changing the pressure of the high-pressure

water supply, and I accomplish this as follows: I may, for example, if a lower pressure is desired, merely apply high pressure water through the water inlet pipe 46 to the 5 annular water space 47. Let it be assumed, for example, that the internal diameter of the casing 39 be the same as that of the casing 20, namely, 18 inches. Let it also be assumed, purely for illustrative purposes, that the diameter of the cut away lower portion of the 10 ram 26a be 12 inches, thus leaving an annular space having a base corresponding to a ring 3 inches from inner to outer periphery. This would make an effective area of 148 15 square inches against which the 1,000 lbs. per square inch of water pressure is applied. This would give a total lift, if water were only allowed to enter the annular space 47 through the inlet 46, of 148,000 lbs., or approximately 20 74 tons. It will thus be seen that the operator has a choice between a total lift of 127 25 tons or of 74 tons with the same source of high-pressure water. Now it is also possible to have water enter both the annular space 47 as well as the cylindrical space 49 through 30 the inlets 46 and 36, respectively, as a result of which the total lift will be equal to 74 plus 127 or 201 tons. Thus there is available to the operator of the press the ability to select 35 any one of three pressures, depending upon the object to be obtained by the operation of the press, that is to say, he may use either the lower water space 49, giving a lift of 127 tons or the upper annular space 47 giving a lift of 74 tons or both simultaneously.

That, however, does not exhaust the possibilities of my improved press. For merely closing, and for low pressure holding, it is possible to use the ordinary 80 lbs. city or 40 plant general pressure which would correspond to a lift on the lower ram head 21, of just about 10 tons. If the ordinary water pressure of 80 lbs. be applied to the annular space 47, this would amount to about 6 tons; 45 if the said low pressure is used in both spaces 47 and 49 the combined lift would be about 16 tons. By using the high pressure in one space and low pressure in another, intermediate values between those given may also 50 be obtained, thus making the operation of the press extremely flexible and bringing out a result not hitherto attained.

When the press is to be opened after a 55 pressing operation, the water pressure is released and leaves the press either through the inlets 46 and 36 or through entirely similar piping installed on the other side of the press diametrically opposite from the inlets but not shown as being sufficiently illustrated by 60 the inlet pipes 36 and 46. The press platen and ram will then sink under the influence of gravity pushing the water out from the annular space 47 and/or the space 49. This, however, is a comparatively slow operation, 65 and I may hasten the descent of the platen

and ram by applying low pressure water to the opposite face of the plunger head 21 by letting water into the annular space 34 through the inlet pipe 45. This, it will be noted, presents another possibility of varying the pressure of the press for it is conceivable that one might apply high-pressure water to the annular space 47 while at the same time opposing the upper lift by applying low-pressure water through the pipe 45 70 so that the upward thrust per square inch will be 1000 minus 80 or 920 lbs. to the square inch.

This feature of being able to reverse the press using the same cylindrical casing 20 as is used for applying the upward pressure is considered by me to be an essential feature of the invention and to be a distinct advance in the art, as thereby the necessity for the separate push-back cylinders is obviated and 80 the entire working mechanism of the press can be contained within the same space as the housing 20 and the thereon superimposed housing 39. This is quite possible by providing the partition 27, thus allowing pressure to be applied to move the ram 26 in either direction. It is to be understood that there might be a number of partitions such as partition 27 and a number of chambers, 85 although I have only shown two in the present application. The mere multiplication of such chambers is to be construed as coming within the scope of my present invention.

In order to enable an operator to control the press so that he may at all times be informed as to the exact pressures obtaining in the various pressure spaces, suitable gages installed in the piping are of course supplied, but these, not forming a part of my invention, 90 are not shown. As already stated, I prefer to control my press by a control device described in copending application, Serial No. 357,736, April 24, 1929, which is so elaborated that the mere movement of a single lever 95 throws into action the various valves, gages, discharge valves, etc. Various modifications of the press as shown may, of course, be made as the same is purely illustrative of the fundamental principle of the invention which 100 consists in so constructing a press that variable lifts will be obtainable with but one high-pressure water supply.

I will now describe the function of the yoke 48 which has been mentioned as being attachable to the lugs 17a and 27a. The purpose of these lugs and the yoke is to allow the press to be partly disassembled so that 105 repairs may be effected to the various gaskets which keep the parts tight against the water pressure, for instance, if it is desired to repair or have access to the gasket 22, which is located in the plunger head 21 and serves to seal the same against the casing 20. Ordinarily this gasket is entirely inaccessi- 110

ble. If it is desired to repair this gasket, the following procedure is followed. First, the bolts 28, holding the transverse partition 27 to the enlarged head of the casing 20, are removed. Then the yokes 48 are put into place, there being preferably four of these, two on each side of the press. Pressure is then applied (low pressure) through the inlet pipe 36 into the space 49. The result of this will be that the ram 26 will be lifted and will push up the platen 17 and by reason of the connection of the latter through the intermediation of the yokes 48 with the partition 27 will lift the latter also. Pressure is applied until the head of the bolt 24 is near enough to the surface of the now open casing 20, whereupon the platen of the press is blocked by suitable blocking means, such as cribbing, whereupon the water pressure may be released and the bolt removed and the packing repaired. It will be noted that this also gives access to the gasket 30 and its retaining means. Thus, by an extremely simple operation it becomes possible to disassemble the press by using its own pressure, something which to my knowledge has not been possible before with presses constructed in accordance with the prior art.

Whilst I have shown a single plunger having a main pressure-receiving head and an auxiliary annular pressure-receiving surface, I do not wish to be limited to the particular construction shown. It is to be considered an equivalent of my invention to have a main press-cylinder and plunger and also a number of auxiliary cylinders, all of which are in operative association with the platen of the press, so that by applying pressure to the auxiliary plungers the total effective lift of the press may be increased. Similarly by using one or two only of the auxiliary plungers then the lift may be comparatively slight.

To illustrate one of these equivalents, I have shown a diagrammatic top view of a platen in Fig. 4. A main, centrally located, plunger 260 may be affixed to the platen 170, and a number (say 4) auxiliary plungers 260a may also be attached to the platen. Any one of these plungers, or any combination of them, may be employed to give a variable lift to the platen of the press. As in the case of the press herein described in detail, but a single high-pressure water supply is required.

In actual practice, the dimensions herein given may be very widely departed from and the press may be built very much larger without departing from the fundamental principle involved, namely, that of the selective pressure principle.

What I desire to have protected by Letters Patent is:

1. In an hydraulic press, two casings, a partition between said casings, a ram ex-

tending through one of said casings and into the other passing through a suitable opening in said partition, a pressure-receiving piston at the end of said ram within the second casing, said piston being in sliding contact with the walls of said casing and making a water-tight seal therewith, a main pressure-chamber at the end of said second chamber being confined by the end thereof and by the said piston, an annular water-space between said second casing and said ram being confined by the opposite side of said piston and the walls of the casing and the partition, said ram being enlarged to substantially the size of the first casing for a distance substantially equal to the length of said first casing but forming therewith an annular pressure-chamber bounded by said enlarged portions the partition and the walls of the first casing, and means for admitting water to said main pressure-chamber and said annular pressure-chamber and said water-space.

2. In an hydraulic press, two casings superimposed upon each other, a partition between said casings, a ram passing through said partition, said ram being smaller than the one of said casings into which it extends but substantially of the same diameter of the other casing from which it extends, a pressure-receiving piston of substantially the same cross-sectional area as that of the first casing and fastened to the end of said ram, a main pressure chamber at the end of said casing, an annular auxiliary pressure-chamber at the end of the other casing nearest the said partition, an annular water-space between the walls of said first casing and said smaller portion of said ram bounded by said partition and the top of said piston, and means for admitting water to said pressure-chambers and said water-space.

3. A selective pressure hydraulic press comprising a casing closed at one end, a partition dividing said casing into two separate chambers, a ram having one end of lesser diameter than the other end so that a shoulder or off-set is formed about midway thereof the wider portion of said ram being in one of said chambers and the smaller portion in the other chamber, a pressure-resisting piston on the end of the smaller portion of said ram and forming with the end of the casing a main pressure-chamber whilst the shoulder on said ram forms with the said partition an annular auxiliary pressure-chamber, a third water-containing chamber being provided by the space bounded by the casing surrounding the smaller portion of the ram, the ram itself, said partition and the reverse side of said piston; a platen attached to the larger end of said ram, vertical supports for guiding said platen, and means for admitting and exhausting water from said main

pressure-chamber and said annular auxiliary chamber.

4. A variable-lift hydraulic press comprising a lower casing, an upper casing, a partition between said casings, laterally extending lugs on said partition, a ram in said casings, a platen supported by said ram, lugs on said platen, and means for connecting the lugs on said platen with those on said partition, whereby the simultaneous movement of said partition and platen may be effected by the operation of said ram.

In witness whereof, I have hereunto subscribed my name.

13 WILLIAM E. McCULLOUGH.
